UNITED STATES PATENT OFFICE.

GEORGE W. HENKEL AND ALFRED B. UPDIKE, OF SAN FRANCISCO, CALIFORNIA.

AIR AND VAPOR SUPPLYING AND CLEANING DEVICE FOR ENGINES.

Application filed August 16, 1923. Serial No. 657,760.

To all whom it may concern:

Be it known that we, GEORGE W. HENKEL and ALFRED B. UPDIKE, citizens of the United States, residing at San Francisco, in the 5 county of San Francisco and State of California, have invented certain new and useful Improvements in Air and Vapor Supplying and Cleaning Devices for Engines; and we do declare the following to be a full, 10 clear, and exact description of the invention, such as will enable others skilled in the art to which it appertains to make and use the same.

This invention relates to an improved device for use in connection with gas engines, 15 more particularly automobile engines, and it comprises means for conveying steam or vapor from the radiator or other sources of steam to the intake manifold, either in a 20 comparatively wet state or in a dry superheated condition.

One object of the invention is to generally improve upon devices of this class by producing one which includes a tank in which a 25 cleaning liquid may be placed, whereby carbon and the like may be effectively removed from the cylinders, spark plugs and valves.

Another object of the invention is to produce a vapor supply and cleaning device 30 which will first permit the cylinders, plugs and valves to be thoroughly cleaned by running the motor, after which a supply of vapor from the radiator or other source, may be fed to the motor to prevent formation 35 of carbon to a great extent.

A still further object is to provide for feeding hot or cold auxiliary air to the motor, instead of vapor, when desired.

With the foregoing in view, the invention 40 resides in the novel subject matter herein-after described and claimed, certain subject matter being common to our United States application, Serial No. 409,273, filed Sept. 9, 1920, and Serial No. 590,519, filed Sept. 45 25, 1922. The present application therefore constitutes a continuation in part of these prior applications.

Figure 1 is a sectional view showing the 50 application of the device to an automobile engine.

Figure 2 is a side elevation of the control valve.

Figure 3 is a horizontal sectional view on line 3—3 of Figure 2.

Figure 4 is a vertical longitudinal section 55 on line 4—4 of Figure 3.

Figure 5 is a vertical transverse section on line 5—5 of Figure 2.

Figure 6 is a similar view on line 6—6 of Fig. 4.

In carrying out our invention, we employ a tank to contain a cleaning liquid when desired, a pipe or tube extending from the steam space of the radiator to the upper end of the tank, a superheater preferably mounted on the exhaust manifold or pipe of the engine, piping extending from the bottom of the tank to the superheater and including a valve, a pipe or tube leading from the superheater to the intake manifold, and a 70 valve-controlled by-pass leading from the piping to the intake manifold, to carry the vapor from the radiator without directing it through the superheater, whenever desired. Provision is also made whereby hot or cold 75 air may be supplied to the motor. The preferred form of construction is shown in the accompanying drawings.

The numeral 1 designates a suitable tank adapted to be mounted on appropriate 80 brackets or the like 2 which are preferably secured to the dash of the machine the upper end of said tank having a filling plug 3 while its lower end may well be provided with a drain plug 4. A steam supply tube or pipe 5 leads from the steam space of the radiator to the upper end of the tank 1 and piping or tubing leads from the lower end of the tank to a superheater 6 which is preferably mounted on the exhaust pipe of the 90 engine. This piping, in the form of the invention herein disclosed, consists of a tube 7 connected to the bottom of the tank 1, another tube 8 connected to the superheater 6 and a valve whose valve body is indicated 95 by the numeral 9. From the superheater 6, a tube 10 leads to Y-coupling 11 which is tapped into the intake manifold. The numeral 12 designates a by-pass tube leading from the valve body 9 to the coupling 11 so that moisture may be sent directly through this tube if desired instead of shunting it down the tube 8, through the superheater 6, and thence through the tube 10 to the intake 100 manifold.

As disclosed most clearly in Figs. 3, 4 and 6, the valve body 9 is provided with a vapor inlet port 13 to which the tube 7 is

connected, with one outlet port 14 from which the tube 8 extends, and with a second outlet port 15 to which the tube 12 is connected. The body 9 is also provided with 5 a cold air inlet nipple 13^a. A rotary valve 16 is located within the body 9 and is provided with a right angular port 17, whereby proper setting of the valve by means of a suitable knob 18, will permit the tube 7 to 10 be placed in communication with the tube 8 when the superheater is to be used or with the tube 12 when it is not desired to send the vapor through said superheater. Also, the nipple 13^a may be placed in communication 15 with either tube 8 or 12 to supply hot or cold air to the engine.

The stem 16^a of the valve 16 passes loosely through an opening in an escutcheon plate 19 adapted to be clamped against the rear 20 side of the automobile instrument board, while the valve body 9 is provided with a flange 9^a secured against the front side of said instrument board, bolts 9^b being used in securing these parts. The rearwardly 25 projecting end of the stem 16^a is threaded into the elongated knob 18 so that the latter may be adjusted according to the thickness of the instrument board, thereby permitting the escutcheon plate 19 to be positioned 30 wherever desired along the stem for contact with the rear side of said board. A set screw 16^b is threaded through the knob 18 for securing the knob and stem together when the necessary adjustment has been 35 made. A coiled spring 16^c surrounds the stem 16^a between the tapered valve 16 and the plate 19 and always holds the valve in proper position within the body 9, regardless of any adjustment of said plate 19 along 40 the stem 16^a. The valve 16 and body 9 are preferably formed with registering openings 16^a (Fig. 4) through which a pin or wire may be passed to hold these parts together prior to installation.

45 The knob 18 is provided with an indicator 20 for co-action with the escutcheon plate 19 so that the valve may be set to supply a hot comparatively dry vapor to the engine, a wet vapor directly from the steam space 50 without passage through the superheater 6, cold air direct from the nipple 13^a through the pipe 12, or heated air obtained by placing part 17 in communication with the nipple 13^a and part 14. Whenever desired, 55 the tank 1 may be filled with a cleaning liquid and the valve 16 is then set so that this liquid will be drawn from the tank through the tubes 7 and 12 to the intake manifold, from which it passes to the engine cylinders to clean the latter in the usual way. As soon as the cleaning operation 60 is effected, hot or cold air, or wet or hot vapor may be supplied to the engine cylinders.

65 Since excellent results have been obtained

from the details disclosed, we prefer to follow these details, but within the scope of the invention as claimed, it is to be understood that numerous minor changes may be made. 70

We claim:

1. In a device of the class described, a cleaning liquid tank, a pipe communicating therewith at the upper end thereof, the free end of the pipe being adapted to communicate with a vapor supply, a superheater, piping extending from the bottom of the tank to said superheater and including a valve, a passage leading from the superheater for connection to the intake manifold of a motor, and a valve-controlled by-pass around the superheater connected at its opposite ends to said piping. 75

2. In a device of the class described, a valve body having a vapor inlet port and two outlet ports, a tank and a tube connecting the lower end of the tank with the inlet port of the valve body, said tank being intended to contain a cleaning liquid when desired, a vapor supply tube adapted to lead 80 from a vapor source and connected to the upper end of the tank, a coupling adapted for connection to the intake manifold of an engine, a fluid heating device, a tube leading from said heating device to said coupling, another tube leading to said heating device from one outlet port of the valve body, and a by-pass tube leading directly to said coupling from the other outlet port of said valve body; together with a valve 85 in said body for placing the inlet port in communication with either outlet port. 90

3. In a device of the class described, a fluid heater, a passage therefrom for connection with an intake manifold of an engine, a second passage out of communication with the heater also adapted to be connected with the intake manifold, a source of vapor, and means for admitting either vapor 95 from said source or air to said heater or to said second passage. 105

4. A structure as specified in claim 2; together with an air inlet port for said valve body adapted to be placed in communication with either of said outlet ports by said 110 valve. 115

5. In a device of the class described a valve body having a vapor inlet port, an air inlet port and two outlet ports, a tank, and a tube connecting the lower end of the tank with the vapor inlet of said valve body, a vapor supply tube leading from a source of vapor and connected to the upper end of said tank, a fluid heating device, a tube leading from said heating device to 120 the intake manifold of an engine, another tube connecting said heating device with one of the outlet ports of said valve body and a by-pass tube leading directly from 125 the other outlet port of the valve body to 130

said intake manifold, together with a valve in said body for placing said inlet ports in communication with either of said outlet ports.

- 5 6. A valve of the character described comprising a valve body adapted to contact with the front side of an automobile instrument board, said body having a bore opening through its rear end, a rotary valve in said body having a stem extending rearwardly beyond the same, an escutcheon plate having an opening through which said stem passes, said plate being adapted to be secured against the rear side of the instrument board, a knob secured to and adjustable along the rear end of said stem to permit adjustment of the escutcheon plate according to the thickness of the instrument board, and means for securing said knob in adjusted position.
- 10 7. A valve of the character described com-

prising a valve body adapted to contact with the front side of an automobile instrument board, said body having a bore opening through its rear end, a rotary valve 25 in said body having a stem extending rearwardly beyond the same, an escutcheon plate having an opening through which said stem passes, said plate being adapted to be secured against the rear side of the instrument board, a coiled spring disposed between the valve and said escutcheon plate, a knob adjustable along the rear end of the stem to permit adjustment of said escutcheon plate according to the thickness of the instrument board, and means for securing 30 said knob in adjusted position.

In testimony whereof we have hereunto affixed our signatures.

GEORGE W. HENKEL.
ALFRED B. UPDIKE.
